CLAIM

The ornamental design for a broom head, as shown and described.

DESCRIPTION

FIG. 1 is a left front underneath perspective view of the broom head;

FIG. 2 is a right back above perspective view thereof; and,
FIG. 3 is a left side view of which the right side is a mirror image thereof.

The broken line portions of the drawings show unclaimed subject matter for illustrative purposes only and form no part of the claimed design.

1 Claim, 3 Drawing Sheets
